CLAIM

The ornamental design for a ground plate for an electrical connector, as shown and described.

DESCRIPTION

FIG. 1 is a top, left, front perspective view of a first embodiment of a ground plate for an electrical connector showing our new design;

FIG. 2 is a bottom, right, rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof;

FIG. 8 is a left side elevation view thereof;

FIG. 9 is a top, left, front perspective view of a second embodiment of a ground plate for an electrical connector showing our new design;

FIG. 10 is a bottom, right, rear perspective view thereof;

FIG. 11 is a front elevation view thereof;

FIG. 12 is a rear elevation view thereof;

FIG. 13 is a top plan view thereof;

FIG. 14 is a bottom plan view thereof;

FIG. 15 is a right side elevation view thereof; and,

FIG. 16 is a left side elevation view thereof.

UNITED STATES PATENT AND TRADEMARK OFFICE
CERTIFICATE OF CORRECTION

PATENT NO. : D714,227 S
APPLICATION NO. : 29/445588
DATED : September 30, 2014
INVENTOR(S) : Buck et al.

Page 1 of 1

It is certified that error appears in the above-identified patent and that said Letters Patent is hereby corrected as shown below:

On the title page at DESCRIPTION, insert the following paragraph:

--In a preferred embodiment, the nature of this product is an electrical component that can take
the form of a ground plate for an electrical connector.--

Signed and Sealed this
Thirtieth Day of December, 2014

Michelle K. Lee
Deputy Director of the United States Patent and Trademark Office
